UNITED STATES PATENT OFFICE.

EMMA BANKOW, OF NEW YORK, N. Y.

NAPKIN HOLDER.

Application filed June 17, 1925. Serial No. 37,633.

This invention relates to improvements in napkin holders for use by women during menstruation periods and the primary object of the invention is to provide a sanitary construction which will grip the napkin and prevent accidental displacement thereof.

Another object of the invention is to provide a construction which allows for expansion, having side portions for holding the napkin and cloth ends which frictionally hold the end of the napkin in place lengthwise.

Further objects and details of the invention will appear from the description of a preferred embodiment of the invention illustrated in the accompanying drawing, in which:—

Figure 1 is a plan view of the open side of a holder in accordance with the present invention;

Figure 2 is a longitudinal sectional view thereof taken on line 2—2 of Figure 1;

Figure 3 is a cross sectional view taken on line 3—3 of Figure 1;

Figure 4 is a sectional view taken on line 4—4 of Figure 1;

Figure 5 is an enlarged sectional view taken on line 5—5 of Figure 1, showing the manner in which the end pocket is stitched to the body portion of the holder.

Figure 6 is a plan view of the holder with a napkin therein;

Figure 7 is a longitudinal, sectional view thereof taken on line 7—7 of Figure 6;

Figure 8 is a cross sectional view taken on line 8—8 of Figure 6; and

Figure 9 is a cross sectional view taken on line 9—9 of Figure 6.

Referring to the drawings, like characters of reference designate corresponding parts in the various views.

The holder in accordance with this invention comprises a longitudinal body portion 10 of rubber, rubberized fabric, or similar material which will not chafe the body of the wearer. Preferably rubberized silk is used with the rubber on the inner side and the silk on the outer side so as to give a soft touch and texture on the skin. The inner layer of rubber waterproofs the material. The body portion has folds at each side, and at each end the body portion has secured thereto a pocket member closed along all sides excepting for the open side of the pocket, which forms a continuation of the

open ends of the body member so that there is one continuously open interior throughout both end pockets and the body member. Into this communicating interior there is placed an absorbent member which extends 60 through the interior of the body member and into the open ends of the closed pockets. The body portion has a longitudinal opening in one side bordered on each side thereof by a longitudinal flat overlapping side strap 65 portion 11 bent outwardly upon a flap portion 12 which it overlies. The closed side 13 extends from the outer edges 14 of said flaps and together with the flap portions 12 engage the napkin. It is to be noted that 70 the body portion 10 and the parts thereof are preferably formed from a flat strip of material by creasing the same to the formation disclosed.

At each end of the body portion 10 is a 75 cloth pocket member 15. Each of the pocket members has its outer end closed, preferably curved in shape and having the marginal edges securely stitched together as indicated at 16. The inner, open end of each 80 pocket is reinforced by stitching 17 and the entire end of the body member is fastened to the pocket by this stitching. It is to be noted that the strap portions 11 and flap portions 12 are connected at their ends by 85 the stitching 17 which will insure the proper holding action on the napkin, (see Fig. 5).

In use, a napkin 18 is placed in the holder as indicated in Figures 6 to 9. It will be 90 noted that the material 18 extends into the pockets 15 at each end and that the pockets will grip the ends thereof. The sides of the material are restricted by the strap portions 11 but the flap portions 12 and closed side 13 open out to receive the contents. When the holder is in position on the wearer, tension on the ends of the pockets 15 is transmitted along the central portions of the straps 11 and tends to hold them in the position shown in Figures 6 and 9. It will be noted that these straps 11 will lie flat against the wearer and the connecting material of the pockets 15, stitching 17 etc., between the ends of the straps directs the lines of force 95 along the center lines of the flaps and prevents them from separating and spilling the contents. The flap portions and side portions 13 will give outwardly for expansion 100 back of the straps and the folds at 14 open 105 110

but the straps 11 operate to securely hold the parts in proper position.

The holder, in accordance with this invention has the advantage that it is clean, 5 easily applicable and properly holds the napkin in place. The holder is cleanable, does away with aprons and rubber bloomers, and holds the wet cloth within the rubber body portion. The holder provides for 10 the use of absorbent cotton instead of rough kotex.

In Figures 1 and 2, a plan view and section of my improved holder is shown. The holder at the top or front has an open entrance side, adapted to permit the entrance of a napkin therein, and when inserted therein, the terminal ends of the napkin enter into the pockets 15, as shown in Fig. 7. As the folds or lateral members 11 and 12, 15 are both secured at their ends to one wall of the pocket as shown in Fig. 5, the upper fold 11, will act as a retaining wall or member, and the other fold 12 will follow to a certain extent the movement of the part 13 20 when the napkin is inserted. This is shown in Fig. 9, where the portion 12 follows the expanding action of the part 13, but the part 11 retains its initial position largely, and thus serves to prevent an opening action of the body member so as to permit the 25 napkin to fall out. This retaining wall 11 holds the napkin in position. This is due largely to the wall 11 taking up the line or pull along the upper wall of the pocket member 15. The opposite walls of the pocket members 15 being in continuation with the wall 13 of the body member, yield 30 with the wall 13.

Thus a very convenient and efficient holder is provided which has closed end pockets 40 but for their open ends which communicate

directly with the interior of the body member and the retaining member 11, arranged as it is in respect to the walls of the pockets serves to hold the napkin from falling out, 45 the members 12 and 13 yielding to the bulging effect of the napkin.

Many other advantages will present themselves to those familiar with the art, and it will be obvious that various changes may be 50 made in the details of construction without departing from the spirit of the invention as defined in the appended claim.

I claim:—

A napkin holder comprising a longitudinal flexible body member closed on the rear side and having side flap portions extending from the edges of the rear side toward each other and towards the central part thereof and folded outwardly upon themselves with 60 the edges thereof in line with the edges of the rear side and forming strap portions overlying said first folded portions, the flap portions and folded portions being substantially of the same width, and parallel with 65 each other, extending lengthwise of the body portion, and a pocket member at each end of the body member and fastened at its rear portion to the rear side of said body and at its upper portion to the flap and 70 strap portions of the body for securing the flap and strap portions together and holding them against separating at their ends, whereby the folded or strap portions serve to hold the napkin on the expansion of the 75 flap portions, and the napkin at its ends is held in the pocket members interposed between the rear side and folded portions.

In testimony that I claim the foregoing as my invention, I have signed my name 80 hereto.

EMMA BANKOW.
